HENRY R. TROTTER, OF MORTON, PENNSYLVANIA, ASSIGNOR TO WESTINGHOUSE ELECTRIC & MANUFACTURING COMPANY, A CORPORATION OF PENNSYLVANIA.

TEMPERATURE-REGULATOR SYSTEM.

Application filed July 19, 1924. Serial No. 727,098.

My invention relates to regulators for dual drive exciter sets and particularly to a temperature regulation system therefor.

One object of my invention is to provide 5 a temperature regulation system that shall return to a neutral position after each operation thereof.

Another object of my invention is to provide 10 a temperature regulation system that shall automatically restore itself to neutral position after the completion of each predetermined operation.

In the operation of large power stations, it 15 is necessary to have a separately-driven exciter for the field windings of the turbo generators. Inasmuch as the continuity of the power output of such generators depends upon the current traversing their field windings being maintained continuously, it has 20 been found necessary to provide both a motor and a small turbine to jointly and severally drive the exciter set. In the event that the voltage of the motor falls below its rated value, a greater proportion of the exciter 25 load is impressed upon the turbine, which, in turn, draws a greater amount of steam.

As a measure of economy, it has been 30 found desirable to conduct the exhaust steam from such exciter turbines into a preheater for the feed water of the station boilers. This practice is so general that, in many power stations, the exhaust steam from the 35 exciter turbines is depended upon almost entirely as a source of thermal energy for the preheaters for the boiler feed water. In such cases, it has been found necessary to increase the steam flow through the turbine in the event that the temperature of the feed water heater falls below a predetermined 40 value.

The present invention relates to a temperature regulation system for controlling the exciter turbine governor in accordance with the thermal conditions in the feed water 45 heater.

The single figure of the accompanying drawings is a diagrammatic view of circuits and apparatus embodying my invention.

My invention comprises, in general, a feed 50 water heater 1 and an exciter steam turbine 2, the exhaust from which is conducted by a conduit or pipe line 3 to the feed water heater, and a temperature regulating system 4 for varying the tension on the turbine 55 governor 5. The turbine 2 is mechanically

connected to one side of an exciter generator 6 and the other side of the latter is connected to a motor 7.

The feed water heater 1 is provided with a thermostat 8 that is connected by a conduit 60 or pipe line 9 to a "sylphon" bellows or thermally-responsive device 11. The thermostat 8, pipe line 9 and "sylphon" device 11 are filled with an expansible fluid such as mercury or ether. One face of the "sylphon" 65 device 11 is attached to a rod 12 that, in turn, is pivotally connected, as at 13, to a floating link 14. One end of the link 14 is pivotally connected to a rod 15 and the other end is pivotally connected to a rod 16 70 that constitutes a plunger for an electromagnet 17.

The rod 15 is pivotally connected to one 75 end of a contact member 18, preferably in the form of a sealed tube containing a conducting fluid 19, such as mercury, the other end of the tube 18 being pivotally mounted on a base member 21. The contact member 18 is provided with pairs of recesses or wells 22 and 23 adjacent to the opposite ends 80 thereof. The middle portion of the contact member 18 is bowed downwardly, as at 24, to form a pool or reservoir for the mercury 19. The wells 22 and 23 are each connected to an electrical conductor that passes through 85 the walls thereof and engages the mercury therein.

The wells 22 are connected in series with the armature of a motor 25 and the field-magnet winding 26 thereof, the latter two 90 being connected in parallel relation. Similarly, the recesses 23 are connected in circuit with the armature of the motor 25 and its field-magnet winding 27. Suitable limit switches 28 and 29 are placed in circuit with 95 the field-magnet windings 26 and 27, respectively. The motor 25 is geared to a gear wheel 31 that is internally threaded and mounted on a worm screw shaft 32, that is adapted to move at right angles to the plane 100 of the gear-wheel 31 when the latter is rotated. One end of the shaft 32 is connected to a spring 33 that, in turn, is connected to the governor 5 and controls the tension thereof. The other end of the shaft 32 is keyed, 105 as at 32a, to an arm 34.

One end of the arm 34 engages a yoke member 35 that is pivotally mounted, as 110 at 36, for controlling the limit switches 28 and 29. The other end of the arm 34 en-

gages a yoke 37 on an arm 38 pivoted, as at 39, to the base of a rheostat or resistor 41. The rheostat 41 is provided with a plurality of terminals 42 that are connected in series with each other between the terminals 43 and 44. The arm 38 is so positioned that it can move across the faces of the several terminals 42, 43 and 44 and effect electrical connection thereto. The pivot point 39 is connected by a conductor 45 to one of the conductors of a supply circuit 46.

The terminals 43 and 44 of the rheostat 41 are connected to terminals 47 and 48, respectively, of the electromagnet 17. The electromagnet 17 is provided with a pair of oppositely wound coils 49 and 51 between which moves an armature 52 that is carried by the plunger 16. The coil 49 is connected in a circuit extending from one of the conductors of the supply circuit 46 to the terminal member 48, the terminal member 53, coil 49, terminal member 47, terminal member 43, terminals 42, arm 38, pivot 39 and conductor 45 to the other side of the supply circuit 46. The coil 51 is connected to one of the conductors of the supply circuit 46 through the terminal 48, coil 51, terminal 54, terminal 44 of the rheostat 41, terminals 42, arm 38, pivot 39 and conductor 45 to the other side of the supply circuit 46.

Assuming that the temperature of the feed-water heater 1 drops below a predetermined value, the "sylphon" device 11 will contract carrying with it the rod 12. Movement of the rod 12 causes the link 14 to turn about the end of the rod 16 thereby raising the contact member 18. Upward movement of the contact member 18 causes the mercury 19 contained in the pool 24 to overflow and connect the wells 22. A circuit is thereupon established that extends from one of the conductors of the supply circuit 46 through one of the wells 22, mercury 19, the other well 22, the armature of the motor 25, to the other conductor of the motor 46. At the same time, the field winding 26 is energized if the limit switch 28 is in its closed position and the motor 25 rotates in a predetermined direction.

Rotation of the motor 25 turns the gear-wheel 31, which in turn, moves the shaft 32 to the left, as viewed in the drawing, and increases the tension on the spring 33. The increased tension on the spring 33 results in a change of position of the weights of the governor 5, which action causes a larger amount of steam to flow through the turbine 2, the pipe line 3, and the feed water heater 1. Such movement continues until the field winding circuit of the motor 25 is interrupted by the limit switch 28 or by the breaking of a circuit in the contact member 18 in a manner hereinafter described.

Longitudinal movement of the shaft 32 to the left, as viewed in the drawing, causes the

arm 38 to turn about its pivot 39 in a clockwise direction, thereby placing a larger number of terminals 42 in circuit with a winding 51 and a smaller number of terminals in circuit with the winding 49. The change in resistance of the circuits including the coils 49 and 51 results in a magnetic unbalance in the electromagnet 17 and the coil 49 predominates over the coil 51 with the result that the armature 52 and the plunger 16 moves upwardly.

Upward movement of the plunger 16 causes the link 14 to pivot about the point 13, which operation moves the rod 15 downwardly and then tends to restore the contact member 18 to its neutral position. At the same time, the increase in temperature in the thermostat 8 causes the "sylphon" device 11 to expand which motion is transmitted by the rod 12 to the fulcrum point 13 causing further downward movement of the right-hand end of the contact member 18.

When the contact member 18 again reaches its horizontal or neutral position, the mercury 19 returns to the well 24 and interrupts the circuit between the wells 22 and, consequently, the circuit through the motor 25 with the result that the latter comes to rest. The parts remain idle as long as the thermal condition in the feed-water heater 1 remains undisturbed.

Assuming the feed-water heater 1 to reach too high a temperature, the "sylphon" device 11 expands and depresses contact member 18 until the mercury 19 makes an electrical connection between the wells 23, whereupon the field-magnet winding 27 and the armature of the motor 25 are energized and the motor rotates in a direction opposite to that heretofore described.

Rotation of the motor 25 moves the shaft 32 to the right of the device, thereby reducing the tension on the governor 5 with a resultant reduction in the amount of steam flow in the turbine 2. At the same time, the arm 38 is turned in a counter-clockwise direction thereby permitting the effect of the coil 51 to predominate over the effect of the coil 49. When the magnetic force of the coil 51 sufficiently predominates over that of the coil 49, the armature 52 and plunger 16 move downwardly, thereby raising the right-hand end of the contact member 18 into its horizontal or neutral position. The circuit between the wells 23 is thereupon interrupted and the motor comes to rest provided the field-magnet winding circuit has not been previously opened by the limit switch 29. The foregoing cycle of operations may be carried on automatically and indefinitely in accordance with the different changes in the temperature of the feed-water heater.

I do not wish to be restricted to the spe-

cific circuit connections or arrangement of parts herein set forth, as various modifications thereof may be effected without departing from the spirit and scope of my invention, I desire, therefore, that only such limitations shall be imposed as are indicated in the appended claims.

I claim as my invention:—

1. In a system of control, a contact device for completing a circuit in any one of a plurality of positions, a motor controlled by the contact device, thermo-responsive means under the control of the motor for moving the contact device from a neutral position to circuit completing positions, and means responsive to the operation of the motor for returning the contact device to its neutral position.
2. In a system of control, a contact device for completing a circuit in any one of a plurality of positions, a motor controlled by the contact device, thermo-responsive means under the control of the motor for moving the contact device from a neutral position to circuit completing positions, and means comprising a differentially wound electromagnet responsive to the operation of the motor for returning the contact device to its neutral position.
3. In a system of control, a contact device for completing a circuit in any one of a plurality of positions, a motor controlled by the contact device, thermo-responsive means under the control of the motor for moving the contact device from a neutral position to circuit completing positions, and means

comprising an electromagnet and a floating link mechanism responsive to the operation of the motor for returning the contact device to its neutral position.

4. In a system of control, a contact device for completing a circuit in any one of a plurality of positions, a motor controlled by the contact device, thermo-responsive means under the control of the motor for moving the contact device from a neutral position to circuit completing positions, and means comprising a multi-wound electromagnet and means for varying the current traversing each of the windings of the electromagnet in response to the operation of the motor for returning the contact device to its neutral position.

5. In a system of control, a contact device for completing a circuit in any one of a plurality of positions, a motor controlled by the contact device, thermo-responsive means under the control of the motor for moving the contact device from a neutral position to circuit completing positions, and means comprising a multi-wound electromagnet, a link mechanism, and a rheostat for varying the current traversing each of the windings of the electromagnet in response to the operation of the motor for returning the contact device to its neutral position.

In testimony whereof, I have hereunto subscribed my name this ninth day of July 1924.

HENRY R. TROTTER.
